UNITED STATES PATENT OFFICE

EMMA RIXTER, OF MARIANNA, ARKANSAS

DESIGN FOR A COMBINED RADIO RECEIVING CABINET, WARDROBE, AND CHIFFONIER

Application filed November 17, 1931. Serial No. 41,755. Term of patent 3½ years.

To all whom it may concern:

Be it known that I, EMMA RIXTER, a citizen of the United States, residing at Marianna, in the county of Lee and State of Arkansas, have invented a new, original, and ornamental Design for a Combined Radio Receiving Cabinet, Wardrobe, and Chiffonier, of which the following is a specification, reference being had to the accompanying drawing, forming part thereof.

The figure is a view in perspective of a combined radio receiving cabinet, wardrobe and chiffonier, showing my design.

I claim:

The ornamental design for a combined radio receiving cabinet, wardrobe and chiffonier, as shown.

EMMA RIXTER.
